BATES TORREY, JR., OF SYRACUSE, NEW YORK, ASSIGNOR TO SEMET-SOLVAY COMPANY, OF SOLVAY, NEW YORK, A CORPORATION OF NEW YORK

PROCESS OF AND APPARATUS FOR RECOVERING THE AMMONIA CONTENT OF COAL-GAS.

1,349,393.

Specification of Letters Patent. Patented Aug. 10, 1920.

Application filed May 3, 1918. Serial No. 232,257.

To all whom it may concern:

Be it known that I, BATES TORREY, Jr., a citizen of the United States, residing at Syracuse, in the county of Onondaga and State of New York, have invented certain new and useful Improvements in the Processes of and Apparatus for Recovering the Ammonia Content of Coal-Gas, of which the following is a specification.

10 My invention relates specifically to the treatment of gas produced by the destructive distillation of coal so as to recover its ammonia content by the passage of the gas through sulfuric acid with consequent conversion of the ammonia into ammonium sulfate.

Any process directed to this end requires the removal from the gas of its tar content which, if allowed to remain would appear 20 as an impurity in the product and also the removal, in recoverable shape, of the fixed ammonia compounds, consisting mainly of chlorid of ammonia, which, if allowed to pass on and be broken up in the acid bath 25 produce chlorin compounds destructive of the apparatus.

The object of my improvements is to accomplish these results in a more simple and economical manner than heretofore and at 30 the same time insure the practically complete recovery in the form of sulfate of the free ammonia content of the gas. To this end in carrying my invention into effect I in the first instance spray the hot gas as it 35 comes from the ovens, in the collecting main, with water in such quantity that a large proportion of it remains in the liquid state in the main. By this means the gas is cooled and the water is highly heated, and eventually, after removing from the gas its tar and 40 fixed ammonia content, I utilize this hot water to again heat the gas and recharge it with water vapor, and free ammonia. In this manner I am able to return to the gas 45 practically all the free ammonia produced in the system without the application of any extraneous heat whatever, with a consequent saving in fuel expense and with great simplicity of operation.

50 The invention will be best understood by reference to the accompanying drawings forming a part hereof, Figure 1 of which is a diagrammatic representation of an organization of apparatus which may be em-

ployed in practising the invention, and Fig. 55 2 is a view on an enlarged scale, partly in section, of means for spraying water into the hydraulic main, reference being made thereto by means of the letters indicating the several parts.

Referring to the drawings, A indicates 60 the collecting or hydraulic main in which the gas is received as it comes from the ovens (not shown in the drawing) through pipes, N. In this the gas is sprayed with water, by well known means, a form of which is shown in Fig. 2, by the vaporization of which the temperature of the gas is reduced to approximately 80° C. A portion of the water is carried along with the 65

gas in the form of vapor while another portion remains in the main in liquid form mixed with the tar therein. The water in the main, A, together with the tar, is drawn off, as by pipe O, to a tank, B, where the tar 70 settles out and is drawn off, while the water overflows to a subsidiary tank, C. The gas from the main passes first to a scrubber, D, wherein it is showered with cooled water of condensation from the gas, this being drawn off from the bottom of the scrubber and 75 continuously forced, as by pump, a, through cooling coils, E, which are showered with cold water, and thence to the top of the scrubber, D. By this scrubbing the gas, 80 which comes from the main at a temperature of approximately 80° C. is cooled. A large proportion of its tar content is removed and much of the water carried thereby is condensed, so that the fixed ammonia 85 compounds, with more or less free ammonia, go into solution.

The hot surplus water of condensation with its tar and ammonia content is drawn off as required by opening valve, b, in pipe, 90 c, and is run to tank, B, and there mixed with the hot water drawn from the main, A.

After this initial scrubbing the gas, which will have been cooled to such low temperature as may be desired, preferably from 100 25° C. to 40° C., is treated to remove any residue of tar remaining therein, as by being forced through a tar extractor, F, of any usual or suitable construction.

The gas is then passed through a scrubber 105 or wash tower, G, in which it is showered with water heated in the hydraulic main, which is drawn from the bottom of tank, C.

thus avoiding the light tar oils which float on the surface of the water in tank, C, and are drawn off by surface overflow to tank, H. The hot water is then forced to the top

5 of tower, G, as by pump, g.

The water enters the scrubber at a temperature of approximately 75° C. and by this scrubbing the previously cooled gas is heated to a temperature of from 65° C. to 10 70°, and is charged with water vapor and takes up and carries along the free ammonia in the wash water. From the wash tower, G, the gas passes to a saturator, I, of any usual or suitable type wherein its ammonia 15 content combines with sulfuric acid to form sulfate of ammonia in the usual manner and the gas passes on to be collected and treated for utilization as desired.

The unvaporized water from the scrubber, 20 G, flows by pipe, i to tank, H, whence it is returned, as by pump, k, through pipe, P, and branch pipes, p, p', to the main, A, to be again used in spraying the gas. Thus a continuous circulation of the water in the 25 system is maintained and the heat imparted to the water by the hot gas in the main, A, is utilized in heating the gas in the scrubber, G, without the application of any extraneous heat.

30 In order to avoid the loss of ammonia in the fixed form due to its concentration and crystallization in the solution a portion of the solution may be drawn off from time to time from tank, H, and treated in any 35 suitable manner as by the well known lime treatment for the recovery of its fixed ammonia content. The ammonia thus liberated may be added to the gas passing from the wash tower, G, to the saturator. The 40 water thus withdrawn from the system and that taken up by the gas in the wash tower, G, may be compensated for by an inflow of fresh water as required from time to time to tank, H.

45 The advantages of my invention will be evident to those skilled in the art since it provides a system extremely simple both in apparatus and method of procedure, in which the tar and free ammonia are automatically separated and the latter recovered in the desired form without the necessity of any critical observation of temperatures and without the use of any extraneous heat to restore the free ammonia to the gas. 50 The ready recovery of the fixed ammonia is also provided for so that there is no loss from this source.

What I claim as new and desire to secure by Letters Patent is:

60 1. The process of recovering the ammonia content of coke oven gas, which consists in heating water in the hydraulic main by the initial heat of the gas as it comes from the ovens, washing and cooling the gas to remove tar and fixed ammonia therefrom, re-

heating the gas by washing it with said heated water and finally passing the gas through an acid bath to form sulfate of ammonia.

2. The process of recovering the ammonia 70 content of coke oven gas which consists in heating water in the hydraulic main by the initial heat of the gas therein, washing and cooling the gas to remove tar and fixed ammonia therefrom by cooling and circulating 75 in contact with the gas water of condensation therefrom, reheating the gas by washing it with said heated water and finally passing the gas through an acid bath to form sulfate of ammonia.

3. The process of recovering the ammonia content of coke oven gas which consists in spraying the gas in the hydraulic main as it comes from the oven with water in such quantity as to leave a material part thereof 80 in liquid form in the main whereby the water is heated, washing and cooling the gas to remove tar and fixed ammonia therefrom by cooling and circulating in contact therewith water of condensation from the 85 gas and returning the surplus water of condensation to the water initially heated by the gas, removing its free ammonia content from the heated water by washing the gas therewith thus heating the gas and adding 90 thereto water vapor and free ammonia and recovering the ammonia from the gas, and returning the surplus wash water to again spray the gas coming from the oven.

4. The process of recovering the ammonia 100 content of coke oven gas which consists in spraying the gas in the hydraulic main as it comes from the oven with water, drawing off the gas from the main and removing tar and ammonia therefrom and thereby heating the water, continuously drawing off and circulating the water from the main and returning it to spray the gas as it comes from the oven therewith and in the course of such circulation washing the gas with 110 the water thereby restoring ammonia thereto and finally passing the gas through an acid bath to form sulfate of ammonia.

5. In apparatus for recovering the ammonia content of coal gas the combination 115 with a hydraulic main and means for delivering gas from coke ovens thereto, of means for showering the gas in the main with water, whereby the water is heated by the gas, means for drawing off the gas 120 from the main and washing and cooling the gas, means for drawing off from the main water heated by the gas therein and washing and heating the cooled gas therewith and means for returning the heated water to the 125 main.

In testimony whereof I have affixed my signature, this 30th day of April, 1918.

BATES TORREY, JR.
